DISPENSING CONTAINER

Michael A. Caruso and Robert Lally, West
Orange, and Joseph V. Roller, South Orange,
N. J.

Application April 27, 1934, Serial No. 722,778

3 Claims. (Cl. 229—17)

This invention relates to an improved dispensing container and one object of the invention is to provide a container in which salt or any other free flowing material may be packed and from which the material may be dispensed without destroying the container.

Another object of the invention is to provide the receptacle or body of the container with a head for its upper end of such construction, that when the receptacle is initially filled and flaps forming the head secured, contents of the receptacle will be confined therein and protected from exposure to moisture but when it is desired to use a portion of the contents, a portion of one flap may be moved out of closing relation to a discharge passage provided through the head.

Another object of the invention is to so form the closure for the discharge passage that it will be initially held in a retracted position but may be torn loose and then freely slid into and out of closing relation to the discharge passage.

Another object of the invention is to provide a dispensing container which may be formed from a single blank of cardboard and very cheaply made.

The invention is illustrated in the accompanying drawing, wherein the same part is designated by the same reference numeral,

Figure 1 is a view of the blank from which the container is made.

Fig. 2 is a top plan view of the container ready to be filled.

Fig. 3 is a perspective view of the container.

Fig. 4 is a perspective view of the container with all but one flap closed.

Fig. 5 is a perspective view showing the flaps all closed.

Fig. 6 is a top plan view showing the flaps closed.

Fig. 7 is a section taken along the line 7—7 of Fig. 6, and

Fig. 8 is a sectional view showing closure strip drawn outwardly to an open position.

This improved container is formed from a single blank of cardboard or other suitable sheet material. The blank which is indicated in general by the numeral 1 is substantially rectangular in shape and is cut from upper and lower edges to form upper flaps 2, 3, 4 and 5 and lower flaps 6, 7, 8 and 9. By folding the blank along the lines 10, 11 and 12 there will be provided wall forming sections 13, 14, 15 and 16 each having flaps at its upper and lower ends which are to be bent inwardly along the lines 17 and 18 to form upper and lower heads for

the container. The extended end portion 19 of the blank projecting from ends of the flaps 5 and 9 is bent along the line 20 to form a tongue or flange which, when glued to the face of the wall section 13 secures the walls in box-forming position. The lower flaps 6 and 8 are then folded inwardly, after which flaps 7 and 9 are swung inwardly one against the other where they are secured by glue and form a multiple-bottom for the receptacle.

The receptacle will now be filled with salt or other free flowing material and the upper flaps folded inwardly to a closed position. The end flaps 2 and 4 are first swung to a closed position, after which the side flap is closed and the flap 3 then swung downwardly upon the flap 5. It should be noted that the flap 4 has an opening 21 cut therefrom and the portion 22 of the flap 3, which is directly above the opening 21 when the flap 3 is closed, is weakened by scoring 23 as shown at 23 in order that this portion of the flap may be readily removed and thereby provide an opening 24 aligned with the opening 21 as shown in Figs. 7 and 8. The portion 22 of the outer flap or ply of the upper head is not to be removed until it is desired to dispense the contents of the container.

A strip 25, which may be referred to as a valve strip or closure, is cut from the flap 5 by slits leading from an end thereof and it should be noted that inner ends of these slits terminate in spaced relation to each other so that the inner end of the strip will be integrally connected with the body of the flap by a small connecting portion or neck 26. The outer end portion of the strip projects from the flap to form a finger hold which projects beyond the wall 13 when the flap 3 is in the closed position and the adjacent end of the flap is cut back as shown at 27 in order that the finger hold may be easily grasped. When the flap 3 is closed it is held firmly in place by glue applied thereto as shown at 28 and the strip 25 will be held in its proper position. As the inner end of the strip is integrally attached to the body of the flap 5 it can not accidentally slide outwardly to an extended position and become lost.

It should also be noted that if the section 22 of the outer flap should be prematurely removed the strip will remain in its retracted position across the openings 21 and 24 and contents of the receptacle can not spill out. When it is desired to dispense a portion of the contents it is merely necessary to grasp the outer end of the strip and by exerting a pulling action tear the strip loose at the neck 26. The strip can then be drawn out.

wardly as shown in Fig. 8 and contents of the receptacle can flow out through the openings 21 and 24 which will then serve as a discharge passage. After a desired quantity has passed out of the receptacle the strip can be returned to its retracted position in which its inner end will extend across the two openings and effectively close the discharge passage. The container can then be placed upon a shelf in an upright position and 10 dust and insects will be prevented from passing into the receptacle. The fact that the strip is disposed between the flap 3 and inner flaps 2 and 4 will cause it to be well supported and as a longitudinally extending slot is formed in the flap 15 5 when the strip is torn loose, the strip will be guided in its sliding movement and retained in position to properly close the discharge passage when in its retracted position.

Although we have herein described a single 20 complete embodiment of our invention, it should be understood that numerous modifications might easily be devised by workers skilled in the art to which this case relates, without departing from the spirit of the invention, as the same is indicated above and in the following claims.

What we claim as new and desire to secure by Letters Patent of the United States is:

1. A dispensing container comprising a receptacle initially open at its upper end and having 30 end flaps and side flaps folded inwardly with the side flaps overlying the end flaps one upon the other and together with the end flaps forming a head for the receptacle having inner and outer upper plies, one end flap being formed with an 35 opening and the outer ply having a detachable portion above the opening for forming a second opening aligned with the first opening, the inner ply having a portion cut therefrom to form a strip extending between the outer ply and end 40 flaps with its outer end projecting to form a finger hold and its inner end detachably held in engagement with the body of the inner ply whereby the strip may be torn loose by pull exerted longitudinally of the strip and drawn outwardly to move

its inner end portion from across the openings and permit dispensing through the openings.

2. A dispensing container comprising a receptacle, a head closing the upper end of said receptacle and having inner plies extending towards each other from opposed walls of the receptacle, an intermediate ply resting against the inner plies and an outer ply covering the intermediate ply and secured thereto, one inner ply having an opening formed therein and the outer ply having 10 a readily removable portion over the opening and when removed forming an outer opening aligned with the inner opening, said intermediate ply having spaced slits leading from one end and defining a strip having a fragment of its inner 15 end integrally united to the body of the inner ply and its outer end portion projecting from an end of the head and constituting a finger hold, a portion of the outer ply above the outer end portion of said strip being cut away whereby the 20 strip may be readily grasped and pulled longitudinally to detach its inner end and draw the strip outwardly to shift its inner end portion out of a closing position across the aligned openings.

25 3. A dispensing container comprising a receptacle, a head for the upper end of said receptacle consisting of flaps carried by walls of the receptacle and folded inwardly one upon another to provide guides and upper and lower plies above the guides, one guide having an opening formed 30 therein and the upper ply having a weakened portion detachable to form an opening lined with the first opening and together therewith forming a discharge passage, and a strip cut from the lower ply and slidably longitudinally between the upper ply and guides into and out of position to dispose a portion across the openings in closing relation to the discharge passage, one end portion of said strip being exposed and constituting a 35 finger hold to be grasped when actuating the strip. 40
